United States Patent Office.

MASON C. AMES, OF HARTFORD, CONNECTICUT, ASSIGNOR TO HIMSELF AND W. EDGAR SIMONDS, OF SAME PLACE.

Letters Patent No. 96,072, dated October 26, 1869.

IMPROVEMENT IN STILTS.

The Schedule referred to in these Letters Patent and making part of the same.

To all whom it may concern:

Be it known that I, MASON C. AMES, of Hartford, in the county of Hartford, and State of Connecticut, have invented a new and useful Improvement in Stilts; and I declare the following to be a full and exact description thereof, reference being had to the accompanying drawings, and to the letters of reference marked thereon, forming a part of this specification.

My improvement relates to the ordinary stilt used by boys, and sometimes by men.

The letter A designates the ordinary stick or bar of wood which forms the upright part of the stilt.

The letter B designates the foot-rest, which is shown in the figure as made of cast-metal, (iron.)

It may as well be made of wood, though, of course, if so made, it cannot be made so light and airy as when made of metal.

The foot-rest B has flanges upon each side, one of which, b, is shown in Figure 1.

These flanges, sliding upon the stick A, keep the foot-rest in proper position.

It will be readily understood that this foot-rest, made as so far described, will readily slide up and down on the stick A.

The letter C designates the clamp-link.

The side c fits under the foot-rest.

The side c¹ has two sharp points, c² and c³. Supposing all the parts to be in the position shown in fig. 1, when pressure is applied downward on the foot-rest, the points c² and c³ will take sharp hold of the stick A, and will support any weight that the foot-rest will bear without breaking.

This clamp-link C is made of metal, either cast or wrought.

It will be readily understood, without further explanation, that in using this stilt the foot-rest can be instantly secured at any desired point on the stick A, and is, therefore, a vast improvement over all other stilts.

I claim, as my invention—

1. The foot-rest B and the clamp-link C, when constructed as described for the purpose described.

2. The combination of the foot-rest B and clamp-link C, when constructed and arranged as described for the purpose described.

3. The combination of the foot-rest B, clamp-link C, and stick A, when constructed and arranged as described for the purpose described.

Dated May 26, 1869.

M. C. AMES.
